UNITED STATES PATENT OFFICE.

CARL E. BRAUN, OF CAMAS, WASHINGTON, ASSIGNOR TO WESTINGHOUSE ELECTRIC & MANUFACTURING COMPANY, A CORPORATION OF PENNSYLVANIA.

REGULATOR SYSTEM.

Application filed June 10, 1922, Serial No. 567,266. Renewed March 27, 1926.

My invention relates to regulator systems and it has special relation to a load-regulating system.

One object of my invention is to provide a system of the above-indicated character that shall function to maintain a substantially constant load upon a dynamo-electric machine.

Another object of my invention is to provide a system of the above-indicated character for a motor that is operated from a power circuit feeding other variable load apparatus, and so governing the operation of said motor that the load taken thereby shall not exceed a predetermined maximum demand upon the power circuit.

Another object of my invention is to provide a system of the above-indicated character that comprises a motor operated from a power circuit supplying other variable load apparatus, and regulating the operation of said motor so that it will utilize only that power not consumed by the other variable load apparatus, within a predetermined limit.

Briefly, the system comprises a pulp grinder operated by a motor that is connected to a power circuit which feeds the apparatus for the entire mill. The load upon the pulp grinder is capable of being regulated so as to maintain the load thereupon substantially constant.

The mill operator may purchase a certain amount of power for which he pays a minimum rate. It, therefore, becomes important that the mill should not consume more than the maximum amount of power to be obtained at the minimum rate. It is not essential that the pulp grinders function to full-load capacity continuously, so that the present invention contemplates providing additional regulating apparatus energized from the power circuit and adapted to control the circuit through the load regulator for the pulp grinder motor so that the pulp grinder motor will consume only as much power within said minimum-rate schedule as is not consumed by the remainder of the mill load. Or, in the event of the mill load being low, the load-regulating apparatus will merely maintain a predetermined full load upon the pulp grinder motor, regardless of the power available for the operation of the motor. Anti-hunting means is provided for the regulating apparatus.

My invention will be best understood from the accompanying drawing, wherein the single figure is a diagrammatic view of the circuits and apparatus embodying my invention.

The present invention is an improvement upon the application of W. G. Mylius, filed June 5, 1922, Serial No. 566,063, and assigned to the Westinghouse Electric & Manufacturing Company, and, in so far as practicable, the same reference numerals will be used herein to designate corresponding parts.

A pulp grinder 1 is adapted to be operated by a motor 2 that is connected to a power circuit comprising conductors 3, 4, and 5. This power circuit is the principal feeder for the entire mill which comprises considerable equipment in addition to the pulp grinders. The load upon the pulp grinder 1 is controlled by a fluid-pressure system indicated generally at 6, the pressure of which is regulated by the operation of a valve 7 that is raised and lowered by a motor 8, through the medium of the illustrated gearing 9. The direction of rotation of the motor 8 is controlled by means of reversing switches 11 and 12.

The switches 11 and 12 are similar in construction so that switch 11 only will be described. This switch has an operating coil 13 and a switch arm 14 that is pivoted at 15. The arm 14 controls main contact members 16 and 17. The shaft of the motor 8 is provided with a friction brake 18 comprising pivoted members that engage the shaft of the motor and are controlled by means of the coil 19. The operating coils 13 of the switches 11 and 12 are respectively connected to the contact members 21 and 22, and the brake coil 19 is connected to the paralleled contact members 20, the circuit through all of which is controlled by means of the regulator 23.

The regulator 23 comprises an arm 24 that is pivoted at 25, and carries on one end thereof a weight 26. Mounted on opposite sides of the pivot 25 are electromagnets 27 and 28. These electromagnets are similar in construction and each comprises a pair of differentially wound coils 29 that are respectively located upon the upper and lower ends of the core armature 30, and a centrally disposed coil 31. The coils 31 are energized from the potential transformer 32 that is

connected across the power circuit 3, 4, 5, thereby polarizing the electromagnets 27 and 28. The coils 29 are adapted to be energized from series transformers 33 and 34 which are connected in the circuit to the motor 2 that is operating the pulp grinder 1, thereby energizing the electromagnets 27 and 28 proportional to the load taken by the motor 2. The load is measured by the 10 watts consumed by the circuit.

The pull of the electromagnets is balanced with respect to the constant power of the weight 26, for which could be substituted a spring or other equivalent means. If the 15 load upon the motor 2 should vary, the variation will be indicated by the value of the current taken by the motor from the power circuit and through the transformers 33 and 34, will be communicated to the electromagnets 27 and 28. The power will either be increased to overcome the action of the weight or decreased so that the weight will overcome the pull of the electromagnets. 20 The result will be to complete the circuit 25 through either contact members 21 or contact member 22 to the respective reversing switches 11 and 12, to operate the motor 8 in the proper direction to restore the load upon the pulp grinder to normal.

In order to prevent hunting action by the regulator, back contact members 35 and 35' are respectively provided for the reversing switches 11 and 12. The contact members 35 control a shunt circuit for a resistor 36 30 that is connected in series circuit relation with the potential coils 31 of the electromagnets 27 and 28, while the contact members 35' control a circuit to a resistor 37 that is adapted to be connected in parallel circuit 35 relation to the potential coils 31 of the electromagnets when the contact members 35' are closed. Thus, the polarization of the electromagnets will be increased or decreased as may be necessary to separate the engaged 40 contact members prior to the obtaining of 45 normal load conditions.

In order to prevent the motor 2 from taking power in excess of the minimum rate, the arm 24 of the regulator 23 is divided by 50 a section of insulation 41 that is located between the contact members 21 and 22. The circuit to the arm 24 on the side of the contact members 22 is normally completed directly from the transformer 32. However, 55 the circuit to the arm 24 on the side of the contact members 21 is completed only through the contact members 42 of the regulator 43. The regulator 43 comprises an arm 44 that is pivoted at 45, and has separate contact members 46 located on the 60 opposite side of the pivot from the contact members 42. The arm 44 carries a weight 47 or equivalent means for exerting a constant pull upon the arm. The regulator 43 65 also comprises electromagnets 48 and 49 that

are disposed on opposite sides of the pivot 45. The electromagnets are similar in construction to the electromagnets 27 and 28 of the regulator 23 and comprise differential coils 51 that are respectively disposed on the 70 upper and lower ends of the core member 52 and are energized from the series transformers 53 and 54. The transformers 53 and 54 are connected in the power circuit ahead of any of the connections for the mill apparatus. The electromagnets also have centrally disposed coils 55 that are energized from the potential transformer 32 in order to polarize the electromagnets 48 and 49. 75

If the power drawn from the feeders 3, 80 4, 5, exceeds a predetermined amount, which is still within the minimum-rate amount, the indication is communicated to the electromagnets 48 and 49 from the transformers 53 and 54. This action will cause the 85 engagement of the contact members 46, thereby operating the reversing switch 12 to remove load from the pulp grinder 1, and reduce the power consumed by the motor 2. A change in the position of the regulator 23 90 is thus effected, so that the contact members 21 will engage each other.

As the mill load decreases, the indication 95 will be communicated to the electromagnets 48 and 49 and cause the closing of the contact members 42. This closure will complete the circuit from the transformer 32 to that portion of the arm 24 that carries the contact members 21. These contact members are already in engagement so that the circuit 100 will be immediately completed to the reversing switch 11 to operate the motor 8, to increase the load upon the pulp grinder 1 and cause the motor 2 to take more current from the feeders 3, 4, 5. When the motor 2 is 105 drawing sufficient power so that the indication upon the transformers 53 and 54 approaches the maximum limit of the minimum-rate amount, the regulator 43 will effect disengagement of the contact members 110 42 and break the circuit to the reversing switch 11, thereby establishing the setting at which the regulator 23 will operate.

It will be apparent that there is nothing 115 interfering with the normal functioning of the regulator 23 to maintain the load upon the pulp grinder 1 substantially constant at the setting that is determined by the regulator 43. If the mill load varies, the apparatus will be caused to function in the 120 manner described to control the load upon the pulp grinder 1 from zero to its full-load capacity.

Modifications in the system and arrangement and location of parts may be made 125 within the spirit and scope of my invention, and such modifications are intended to be covered by the appended claims.

I claim as my invention:—

1. In a regulator system, the combination 130

- with a power circuit, a motor connected thereto, a variable load operated by said motor, means for controlling the amount of said load and means comprising a motor-operated valve, switches for governing the rotation of said motor, and means for selectively operating said switches, said selective means comprising a pair of differential electromagnets energized proportional to the load upon said motor, of means for also selectively operating said switches, said means comprising a pair of differential electromagnets energized in accordance with the load upon said power circuit. 5
- 18 2. In a regulator system, the combination with a power circuit, a motor energized therefrom, a variable load operated by said motor, means for controlling said load and electroresponsive means for governing said controlling means, of additional means for controlling the circuit through said electroresponsive means, said additional means being controlled in accordance with the load upon said power circuit. 20
- 25 3. In a regulator system, the combination with a power circuit, a dynamo-electric machine connected thereto, a variable load connected to said machine, and means for controlling the amount of said load comprising a pair of switches, said means being governed in accordance with certain electrical characteristics of said power circuit and of said machine to govern the operation of said switches. 30
- 35 4. In a regulator system, the combination with a power circuit, a dynamo-electric machine connected thereto, and means for controlling the operation of said machine, of additional means for also controlling the operation of said machine, said additional means being governed in accordance with the watts of said power circuit and controlling the circuit of the first-mentioned means. 40
- 45 5. In a regulator system, the combination with a power circuit, and a dynamo-electric machine connected thereto, of means for controlling the operation of said machine, said means comprising regulator mechanism governed in accordance with the operation of said machine, regulator mechanism governed in accordance with the load upon said power circuit, and contact members operated by each of said mechanisms, the circuit controlled by said regulators extending through the contact members of each regulator. 50
- 55 6. In a regulator system, the combination with a pulp grinder, a motor for operating the same, a power circuit to which said motor is connected, a motor-operated valve for controlling the amount of load upon said pulp grinder, and regulating means for controlling the operation of said valve to maintain substantially constant load upon said motor, of additional means for govern- 60
- ing the control circuit of said regulating means and operating proportional to the load upon said power circuit. 70
7. The combination with a power circuit, a plurality of variable load devices connected to said power circuit and adapted to operate within a predetermined power limit, of a pulp grinder, a motor for operating said grinder and connected to said power circuit, regulating means for said motor comprising switching mechanism, and means for governing the operation of said motor proportional to the load upon said power circuit, said governing means also controlling the operation of said switching mechanism. 75
8. In a regulator system, the combination with a power circuit, and a motor energized therefrom, of regulating means for said motor comprising a pair of switches, mechanism operated in accordance with the load upon said motor, and mechanism operated in accordance with the load upon said power circuit, said mechanism conjointly controlling said switches. 85
9. In a regulator system, the combination with a power circuit, and a motor energized therefrom, of regulating means for said motor comprising switching apparatus, mechanism operated in accordance with the load upon said motor, mechanism operated in accordance with the load upon said power circuit, and contact members respectively controlled by said mechanisms, the energizing circuit for said switches including both mechanisms. 95
10. In a regulator system, the combination with a power circuit and a motor connected thereto, of regulating means for said motor comprising a pair of switches, electroresponsive means operated in accordance with the load upon said motor and adapted to govern said switches so as to maintain a substantially constant load upon said motor, and electroresponsive means operated in accordance with the load upon said power circuit and adapted to govern said switches so as to limit the operation of said motor within a predetermined load upon said power circuit. 105
11. In a regulator system, the combination with a power circuit, and a motor energized therefrom, of regulating means for said motor comprising a pair of switches, mechanism operated in accordance with the load upon said motor mechanism operated in accordance with the load upon said power circuit, said mechanism conjointly controlling said switches, and anti-hunting means co-operating therewith. 110
12. In a regulator system, the combination with a power circuit and a motor energized therefrom, of regulating means for said motor comprising switching apparatus, mechanism operated in accordance with the load upon said power circuit, said mechanism conjointly controlling said switches, and anti-hunting means co-operating therewith. 115
13. In a regulator system, the combination with a power circuit and a motor energized therefrom, of regulating means for said motor comprising switching apparatus, mechanism operated in accordance with the load upon said power circuit, said mechanism conjointly controlling said switches, and anti-hunting means co-operating therewith. 120
14. In a regulator system, the combination with a power circuit and a motor energized therefrom, of regulating means for said motor comprising switching apparatus, mechanism operated in accordance with the load upon said power circuit, said mechanism conjointly controlling said switches, and anti-hunting means co-operating therewith. 125
15. In a regulator system, the combination with a power circuit and a motor energized therefrom, of regulating means for said motor comprising switching apparatus, mechanism operated in accordance with the load upon said power circuit, said mechanism conjointly controlling said switches, and anti-hunting means co-operating therewith. 130

load upon said motor, mechanism operated in accordance with the load upon said power circuit, contact members respectively controlled by said mechanisms, the energizing circuit for said switches including both mechanisms, and anti-hunting means co-operating therewith.

13. In a regulator system, the combination with a power circuit and a motor connected thereto, of regulating means for said motor comprising a pair of switches, electroresponsive means operated in accordance with the load upon said motor and adapted to govern said switches so as to maintain a substantially constant load upon said motor, electroresponsive means operated in accordance with the load upon said power circuit and adapted to govern said switches so as to limit the operation of said motor within a predetermined load for said power circuit, and anti-hunting means co-operating therewith.

14. In a regulator system, the combination with a power circuit and a motor connected thereto, of regulating means for said motor comprising switching mechanism, electroresponsive means for operating said switching mechanism, anti-hunting means cooperating therewith, and a second electroresponsive means energized in accordance with the load on said power circuit for operating said switching mechanism to limit the operation of said motor so as not to exceed a predetermined load on said power circuit.

15. In a regulator system, the combination with a power circuit, a motor connected thereto, a variable load operated by said motor, means for controlling the amount of said load and comprising a motor-operated valve, switches for governing the rotation of said motor, and means for selectively operating said switches, said selective means com-

prising a pair of differential electromagnets energized proportional to the load upon said motor, and means adapted to prevent hunting action, of means for also selectively operating said switches, said means comprising a pair of differential electromagnets energized in accordance with the load upon said power circuit.

16. In a regulator system, the combination with a power circuit, a motor energized therefrom, a variable load operated by said motor, means for controlling said load and electroresponsive means for governing said controlling means, of additional means for controlling the circuit through said electroresponsive means, said additional means being controlled in accordance with the load upon said power circuit, and anti-hunting means co-operating therewith.

17. In a regulator system, the combination with a power circuit, a dynamo-electric machine connected thereto, a variable load connected to said machine, and electroresponsive means comprising a circuit for regulating the amount of said load, of additional means responsive to power circuit conditions for controlling the circuit through said electroresponsive means, and anti-hunting means co-operating therewith.

18. In a regulator system, the combination with a power circuit, a dynamo-electric machine connected thereto, and means for controlling the operation of said machine, of additional means for also controlling the operation of said machine, said additional means being governed in accordance with the watts of said power circuit and controlling the circuit of the first-mentioned means, and anti-hunting means co-operating therewith.

In testimony whereof, I have hereunto subscribed my name this 29th day of May, 1922.

CARL E. BRAUN.
